UNITED STATES PATENT OFFICE

ESTEBAN GOLA, OF BUENOS AIRES, ARGENTINA

PLIABLE HAMMOCK CHAMBER FOR STEAM BATHS

Application filed November 8, 1929, Serial No. 405,808, and in Argentina September 17, 1929.

The different types of means for giving steam baths that include all the body are well known, amongst which, those most commonly used consist in chambers in which the person is seated in such a way that the upper part or wall of the chamber allows the head to be kept above so that the steam circulates freely inside, coming in contact with the body.

This steam is generated in the chamber by

10 a suitable heater that vaporizes the existing water in a suitable container; these chambers are portable and are generally made with a framework of wood covered with canvas or the like, in the form of curtains 15 appropriately joined at the corners.

Practically, they present objections by the inconvenience of providing the steam source, putting it in activity and leaving it in suspension, and also produce some fatigue to 20 the person bathing, who generally needs another to help in the preparation and further necessary details.

Further, there are steam leakages through the curtains, and the bath does not give the 25 profitable results that are expected from it.

The present invention is in the form of a bed in combination with a steam source, upon which the person who is to have the bath lies, and is characterized amongst other 30 particularities by being pliable, thereby occupying a very small place when not used, and easily transportable from one place to another; this bed at the upper part has arches over which is laid, for instance, a 35 woolen blanket that does not allow the steam to filter through, and which totally covers the bed, but leaves free the head of the person who is bathing.

When the bed is set up, a chamber is 40 formed, and the steam is provided inside by means of a perforated pipe, to which steam arrives which has been generated by a boiler placed at some distance, from which by 45 means of a rubber pipe or the like, is made the connection from this source of steam, to the pipe line of the chamber. A steam tap situated in the pipe within reach of the person bathing, opens and cuts off, as the 50 case may be, the passage of the steam from the boiler to the pipe line.

As has been described, the invention meets satisfactorily the purposes of its creation, because the source of the steam is placed far from the chamber, it is very convenient to take the bath, and the handling of the provision and suspension of the current of steam is very practical; also because when the person is lying on the bed, he bathes in perfect rest.

Other advantages that the bed has, is that it serves as an ordinary bed when it is not being employed for what it is preferably intended.

In the accompanying drawings given in illustration of contents of this invention:

Figure I is a side view of the bed mounted, 65 forming a chamber, and constructed according to the invention.

Figure II shows a boiler to generate the steam that penetrates to the interior of the chamber.

Figure III is a longitudinal cut of the bed shown in the Figure I.

Figure IV is a transverse section according to the line A—B of Figure I.

Figure V shows the bed seen from above.

Figure VI shows a perspective of the folded bed, having one of the longitudinal walls opened to show the invention more clearly and

Figure VII is a front and profile view of 80 the hinges by means of which the head and foot pivot.

The construction of the bed is the following:

The material principally employed is 85 wood and the parts, one with another, are appropriately joined.

The main body has a structure with a frame 1 that carries cross beams 2 upon which are placed longitudinal rods 3 properly spaced, in such manner that they form the bed itself on which the person lies. At each one of the sides, or cuts, which will be called heads, pivot walls 4—5 on hinges 6, Fig. VII, of special construction disposed in 90 the upper angles, so that when the walls 4—5 fold, they remain beneath the level of the edge of the frame in such a way, that the longitudinal walls 7 that also pivot in the same way, by means of the hinges 8 placed 100

in the corners. In folding, they cover the walls 4—5 of the heads, so that the bed when folded forms a rectangular parallelopiped.

On unfolding the bed, the longitudinal walls 7 and the transverse ones 4—5 form the chamber for the distribution of the steam, because they maintain a vertical position with the edges of the corners touching each other.

The transverse walls 4—5 have on the inside, extending downwardly, projections 9 with grooves 10 in which engage in removable form plates 11 which are provided at the ends with a pipe 12 with equidistant perforations 13, an inlet 14, and a small pipe 15 for the evacuation of the water; and this pipe which serves to distribute the steam, is utilized at the same time to reinforce the walls 4—5 to maintain their rigidity and to avoid any rocking movement that would make the bed swing.

The pipe 12 has a lateral extension 16 that unites in the socket 14 and in this extension 16 is encountered the steam tap 17 that admits or cuts off the passage of the steam that comes from the boiler. By means of a rubber pipe, one of its ends 18 is joined by a joint with that end of the pipe 16 which goes out from the pipe 12.

Some portion 19 of the longitudinal rods 3 is cut and leaves a space by the side of the head through which the person who is bathing can introduce his hand to turn the steam tap 17.

At the upper part of the frame 1 are encountered two lugs 20 to each side to secure the ends of two arches 21 that remain above to serve as support to the blanket that is laid over it and that forms the vaulted space beneath where the bathing person is placed.

A movable board 22 pivoted by means of the hinges 23 is arranged in the upper part of the heading of the frame and serves to contain the pillow on which the bather can recline. This board 22 can be maintained to level of the bed, rising or descending being kept in position by a support 24 that pivots at an end 25 and in the board 22 and at another 26 is placed as desired by teeth 27 that the wall has, so making a support.

The boiler utilized in combination with the bed consists of a framework 28 that holds the container that forms the boiler 29, and this combination has a holder 30 to facilitate the transportation. Beneath is the means of generating the heat and the tank or boiler 29 has at its upper part a removable cap 32 for use when water is to be put in, and a curved pipe 33 in which is connected the rubber pipe 34 that leads to the pipe 12 for the distribution of the steam. It has also a manometer 35 to indicate the pressure of the steam, an exhaust valve 36 for the super-production, a glass pipe or level 37 to take account of the existing water in the interior, and an evacuation cock 38.

As it will be easily understood, this apparatus is placed near or far from the bed, according to the rubber pipe 34 that puts it in union with the latter.

The way to proceed with the pliable bed to take a bath and the operation and the circulation of the steam for the purpose will be described as follows.

The bed being in the represented condition in the Figure VI and supposing that one of the longitudinal walls 6 should also be folded as one of them is represented in said figure, we will proceed to open the whole, so that the four walls 4—5—6 maintain the vertical position, as is demonstrated in Figure I, seen from the side. When so placed we take the pipe of distribution 12 of the steam and by means of the plates 11 that are at its ends, proceed to engage in the grooves 10 of the interior projections 9 of the transverse walls 4—5, which causes the bed to remain perfectly firm, the edges of the corners of the walls 4—5—6 meeting each other.

After this board is placed, which as has been said, has hinges 23 of special construction and by means of the support 24 that engages in the teeth 27 of the wall 5 the desired incline is given to the board 22 placing at once the arches 21 secured at the lugs 20 and above these the blanket or similar cloth that prevents the filtration of the steam.

Immediately after we light the heater 31 of the boiler 29, which will be already communicated with the bed by means of the rubber pipe 34 and according to the indicating apparatus that the said boiler 29 possesses, the level of the water that has been thrown by the mouth 32 is estimated and the pressure of the steam is observed by means of the manometer 35.

The steam passes then by means of the rubber pipe 34 and reaches the steam tap 17 situated beneath the open space 19 in the bed. Then is the suitable time for the person to enter the bath, lying in the bed beneath the blanket, and with his hand opens the steam tap 17 by means of which the steam begins to enter the distributing pipe 12, escaping by the orifices 13. The quantity of steam, time of remaining in the bath and other details remain to be decided by the bather, and when he considers that sufficient time has passed, he closes the steam tap 17 and the bath is finished.

From what has been previously expressed regarding the construction and what immediately follows can be clearly deduced that to return the bed and the boiler to the situation of resting, the manipulations are reversed thereby it is considered unnecessary to give a detailed description respecting them.

What I claim is:

1. A chamber for a steam bath comprising a structure formed of a rectangular frame with cross beams, the shorter sides being piv-

totally secured to the said frame, walls on the said frame foldable underneath the edge of the frame when the chamber is in its collapsed position, longitudinal walls pivotally connected to the frame and foldable underneath the shorter walls; a pivotal head rest supported on one of the shorter walls; a perforated steam pipe, plates on the end of the said pipe for aiding the distribution of steam, projections on the interior walls of the framework having a groove therein and engaging with the said plates, whereby they also aid in reinforcing the said walls, a pliable bed formed of substantially equidistant longitudinal rods disposed on said frame, the said bed having an opening in the head thereof, lugs on the said frame, arch members removably carried by said lugs, and a pliable covering on the said arch members.

2. A chamber for a steam bath comprising a structure formed of a rectangular frame having longitudinal and transverse pivotal walls, movable when the chamber is opened, into vertical position with abutting contact of their adjacent edges, cross beams on the said frame, a pliable bed formed of substantially equidistant longitudinal rods disposed on said frame, the said bed having an opening at the head thereof, the walls thus forming a chamber beneath the bed, lugs on the said frame, arch members movably carried by said lugs, a pliable covering on the said arch members, a removably mounted articulated head rest secured to said frame adjacent the opening, a removable pipe arranged below said bed and having substantially equidistant perforations and an orifice, a branch departing from said pipe into the said opening, a steam pipe on said branch and lying in said opening, the said branch extending through one of the said walls, and a steam supply to which the said branch is connected.

3. A chamber for a steam bath comprising a foldable rectangular frame, cross beams therefor, a pliable bed formed of substantially equidistant longitudinal rods disposed on said frame, the said bed having an opening at the head thereof, lugs on the said frame, arch members removably carried by the said lugs, a pliable covering on the said arch members, a removably mounted articulated head rest secured to said frame adjacent the opening, means on said frame by which to carry it in transport, a boiler carried by said frame, heating means disposed beneath said boiler, an evacuation cock, a manometer, a valve for the super-production of steam, a pipe for the outlet of the steam into the chamber, and means connecting the said pipe to the said boiler.

In testimony whereof I affix my signature.
ESTEBAN GOLA.
